[57] **ABSTRACT**

[22] Filed: July 6, 1971

A blank to be coned into a burner plate for a forced draft burner has rows of openings extending thereacross. Strips are formed having a longitudinal rib with wings at each side of the rib. Each strip is positioned with its rib between a respective pair of rows of openings, and secured to the plate, with the wings projecting outwardly over said rows to form expansion chambers. The blank with the strips thereon is then coned.

BURNER PLATE, IN PARTICULAR FOR FORCED-DRAFT OILGAS OR GAS BURNERS

BACKGROUND AND SUMMARY OF THE INVENTION

The invention relates to a burner plate of conical shape constructed from a flat sheet metal blank of perforated plate, in particular for forced-draft oilgas (gasified oil) or gas burners.

Burner plates produced from perforated sheet are known. Such burner plates may be flat or they may be shaped in the form of a spherical section or of a truncated cone. A flat burner plate has no form stability. Moreover, it suffers from the disadvantage that dust (e.g., soot), which drops from the burner shaft, is deposited on the burner plate and may thus impair the apertures. The middle zone of a spherical burner plate is subject to the same defects since the dust, which drops onto the said middle zone, may also clog the apertures. The dust is able to slide outwardly only on the inclined parts of the spherical burner plate. As regards the accumulation of dust, the conical shape is better since the dust particles are able to roll off from all sides of the burner plate aperture surface.

Fresh air is supplied to the fuel in forced-draft oilgas or gas burners after preheating in a mixing chamber. The mixing chamber is covered by a burner plate in the form of an outlet cone.

It is known that the flames emerging from said apertures in the burner plate occasionally tend to lift off. It is furthermore known that such lift-off of the flames may be avoided by the use of expansion chambers causing stable and adhering flames to be formed on such chambers. Such expansion chambers are formed by means of sheet metal strips attached to the burner. Such stable and adhering flames prevent lift-off of the main burner flames.

Sheet metal strips for forming expansion chambers cannot, however, be easily attached to a burner inlet surface of conical shape. For example, if sheet metal strips to form expansion chambers are to be applied to a burner plate of conical shape along the surface lines of the said cone, the adjacent ends of the strips in the area of the cone apex would all be positioned closely adjacent each other so that no surface would remain for the main flame. At the base of the cone, on the other hand, the areas of the cone having apertures for the main flames would be so large that part of the main flame would remain unsupported by an adhering flame.

The object of the invention is to provide a burner plate of conical shape, constructed from a flat sheet metal blank, having sheet metal strips for forming expansion chambers so that adhering flames, uniformly distributed over the burner plate surface, may be produced.

According to the invention this is achieved in that straight sheet metal section strips for forming the expansion chambers are placed upon the flat sheet metal blank forming the burner plate and are deformed together therewith so that adhering flames, preventing lift-off of the flame from the burner plate, are produced in uniform distribution over the surface of the conical burner plate after shaping into a cone.

The sectioned sheet metal strips may be attached to the top of the burner plate. However, in view of the problem of dirt accumulation it is advantageous if the

sectioned sheet metal strips are positioned on the underside of the burner plate.

The sectioned sheet metal strips may have a rib extending longitudinally midway between two straight rows of apertures of the sheet metal blank and joined to the blank. Said strips have flat edges on both sides of the rib, with the edges being slightly inclined towards the sheet metal blank and extending over said rows of apertures.

DESCRIPTION OF THE DRAWING

FIG. 1 is a vertical section through a mixing chamber for a forced-draft oilgas burner with a surmounted burner aperture plate of conical shape according to the invention;

FIG. 2 is an enlarged section through the burner plate and showing the sectioned sheet metal strips which form the expansion chambers;

FIG. 3 is a plan view of FIG. 2; and

FIG. 4 shows the sheet metal blank of perforated plate with the surmounted sheet metal strips prior to being shaped into the conical burner plate.

DESCRIPTION OF SPECIFIC EMBODIMENT

In FIG. 1 the numeral 1 refers to a mixing chamber for a burner and formed from a truncated conical shell 1a. At its bottom this shell is attached to brackets 2 secured to a guide sleeve 3 of a gas nozzle or an oil spraying nozzle 4. At the top the mixing chamber is closed by a conical upper burner plate 8 of perforated sheet metal. Plate 8 has an apex angle which is relatively large compared to the apex angle of the truncated conical shell 1a. The lower cone 1a of the mixing chamber has apertures 5 for the entry of forced air into the chamber 1. Air also enters through an aperture 5' at the lower end of the lower cone. The forced air draft is passed in known manner, not shown, from the outside at the top downwardly along a heating shaft shell 6 of the combustion chamber 7 where the air is heated before being conducted into the mixing chamber 1.

The conical burner plate 8 is positioned at the bottom of a combustion chamber 7 defined by the heating shaft shell 6. A flanged edge 8' of the burner plate 8 bears sealing-tight at 9 on the heating shaft shell 6. The mixing chamber shell 1a is joined at 10 to the burner plate 8.

Sheet metal strips 11 are spot-welded on the underside of the burner plate 8 and form expansion chambers 15. The sheet metal strips 11 have a rib 12 disposed along their middle line with wings extending outwardly at each side of the rib. This rib can be formed by embossing (roll forming) or by bending the metal in a brake. This rib bears against the burner plate 8 and is positioned between two straight rows of apertures 13. The wings of the sheet metal strip 11 on both sides of the rib 12 are slightly inclined towards the burner plate and extend over the aforementioned rows of apertures 13. In this way, expansion chambers 15 are formed. The fuel mixture enters into chambers 15 through gaps 14 from the mixing chamber 1. Accordingly, the fuel mixture expands in the chamber 15 (because the inlet area is smaller than the outlet area) and emerges at reduced velocity through the apertures 13. Adhering flames are therefore formed on the apertures 13 which prevent the adjacent main flames, supplied directly

from the mixing chamber 1 and emerging from the apertures 16, from lifting off.

As shown in FIG. 4, the burner plate 8 is constructed of a circular sheet metal blank 17 having a sector-shaped cut-out defined by edges 18. The sheet metal blank is perforated to form openings 13 and 16 (only a few of which are shown in FIG. 4). The sheet metal strips 11 are positioned parallel to each other at identical spacings on the sheet metal blank. The sheet metal blank is then formed into a cone, the edges 18 of the said cone being joined to each other by means of hard soldering. The deformation of the flat blank into a cone is also accompanied by a corresponding co-deformation of the sheet metal strips 11. This feature, however, does not alter the fact that the adhering flames are uniformly distributed over the surface of the burner plate.

As already mentioned, it is advantageous if the sheet metal strips are so disposed that they are situated on the interior or underside of the burner plate 8. This is advantageous in view of the risk of dirt pollution. If the sheet metal strips 11 are surmounted on the outside of the burner plate 8, the fuel mixture will flow through the apertures 13 and the expansion chambers 15 and the adhering flames will emerge from the gaps 14.

We claim:

1. In a forced-draft burner having a mixing chamber which terminates in a burner plate of conical configuration made from a metal blank having rows of openings

10
15

therethrough which is then cone bent to form the burner plate, the improvement wherein said blank has a plurality of straight metal strip means extending substantially parallel to each other in juxtaposition to some 5 of said rows of openings and forming expansion chambers between the blank and the strip means, parts of said strip means being spaced from said blank to define gaps for the passage of fluid, said strip means being bent along with the blank when the plate is formed.

2. In a burner as set forth in claim 1, wherein said strips are on the mixing chamber side of said plate.

3. In a burner as set forth in claim 2, wherein each said strip has a rib projecting outwardly at one side thereof, said rib being against said plate and secured thereto, each said strip having wings extending outwardly and spaced from said plate with said spacing being greater at the rib end of the wing than at the distal end of the wing, each said wing being over a row of openings.

20
25
4. In a burner as set forth in claim 1, wherein each said strip has a rib projecting outwardly at one side thereof, said rib being against said plate and secured thereto, each said strip having wings extending outwardly and spaced from said plate with said spacing being greater at the rib end of the wing than at the distal end of the wing, each said wing being over a row of openings.
